Primary Examiner — John Windmuller(74) Attorney, Agent, or Firm — Carter, DeLuca, Farrell & Schmidt LLP(57) CLAIM

The ornamental design for a fountain grill cleaner, as shown and described.

DESCRIPTION

FIG. 1 is a top plan view of a fountain grill cleaner showing my new design;

FIG. 2 is a front elevational view thereof, the rear elevational view being a mirror image thereof;

FIG. 3 is a bottom view thereof;

FIG. 4 is a left end elevational view thereof; and,

FIG. 5 is a right end elevational view thereof.

The broken lines shown and the areas enclosed by the broken lines and without shading are included for the purpose of illustrating portions of the fountain grill cleaner that form no part of the claimed design.

The dot dash lines represent a boundary between the claimed and unclaimed areas.
